UNITED STATES PATENT OFFICE.

ULRICH REIFFER, OF KANSAS CITY, MISSOURI.

REFRIGERATOR ICE-HOLDER AND WATER-ESCAPE.

SPECIFICATION forming part of Letters Patent No. 401,589, dated April 16, 1889.

Application filed July 27, 1888. Serial No. 281,172. (No model.)

To all whom it may concern:

Be it known that I, ULRICH REIFFER, of Kansas City, in the county of Jackson and State of Missouri, have invented a certain 5 new and useful Improvement in Refrigerator Ice-Holders and Water-Escapes, of which the following is a full, clear, and exact description, reference being had to the accompanying drawings, forming part of this specification, and in which—

Figure I is a top view illustrative of my invention. Fig. II is an end view and shows the opening through which the ice is passed. Fig. III is a cross-section taken on line III 15 III, Fig. I. Fig. IV shows side and end views of one of the ice-carrying bars with the water-shed attached to its lower side. Fig. V is a similar view to Fig. IV, but which has a trough attached to its lower side. Fig. VI is a longitudinal section taken on line VI VI, Fig. I.

My invention relates to a device for holding ice in a refrigerator and means for catching and conveying the water away as the ice melts; and my invention consists in features 25 of novelty, hereinafter fully described, and pointed out in the claims.

Referring to the drawings, 1 represents the outside frame or case of the box, and 2 3 are a series of bars which reach from one side of 30 the box to the other, and on which the cakes of ice are supported.

4 5 are cleats secured to the ends of the box, and on which the bars 2 3 rest. To each of the bars 2 is attached a trough, 6. These 35 bars 2 are slightly inclined, as shown in Fig. VI, and the upper ends of the troughs 6 fit snugly into notches 7 in the cleat 4 and the lower ends rest squarely on the cleat 5.

To each of the bars 3 is attached a water-shed, 8, and as the bars 2 and 3 alternate the shed on one will drip into the troughs of the others. (See Fig. III.) The upper ends of the bars carrying the water-sheds rest on pointed standards 9, which in turn rest on the cleat 4, 45 and the lower ends of the bars have a square extension, 10, which rests on the cleat 5.

11 are metal straps by which the water-sheds and the troughs, respectively, are attached to the bars.

50 12 is an end trough attached to the cleat 5, into which the troughs 6 drain, and from which the water is carried off to any point desired by means of a pipe, 13.

14 is a fence placed around on the inside of the box, which prevents the ice from coming 55 up against the sides of the box, so that when it melts the water will be prevented from running down the sides of the box.

I claim as my invention—

1. In a refrigerator, the combination of the 60 box, a series of ice-supporting bars placed crosswise of said box, troughs, one attached to and arranged under each alternate bar, and water-sheds, one attached to and arranged under each intervening bar and projecting over said troughs, substantially as 65 and for the purposes set forth.

2. In a refrigerator, the combination, with the box, of a series of ice-supporting bars placed within the box, troughs, one arranged 70 directly under each alternate bar, straps 11, attached to each alternate bar and to the inside of the trough below, and water-sheds, one attached to and arranged under each intervening bar and projecting below the edges of 75 said troughs, and a conducting-trough into which the said troughs drain, substantially as set forth.

3. In a refrigerator, the combination, with the box, of the cleats 4 and 5 in said box, the 80 ice-supporting bars 2, supported upon cleat 5, troughs beneath said bars and attached thereto and resting upon cleat 4, the ice-supporting bars 3, water-sheds beneath said bars and attached thereto, the standards 9, resting upon one of said cleats and supporting said bars 3 at one end, and the extensions 10, attached to said bars 3 and resting upon the other cleat, substantially as set forth.

4. In a refrigerator, the combination, with 90 the box, of the bars 2 3, arranged alternately across said box, the bars 3, having longitudinal grooves, the troughs 6, arranged below the bars 2, the straps 11, attached to bars 2 and to the inside of said troughs, water-sheds fitted in said longitudinal grooves and projecting downwardly beyond the edges of said troughs, the cleat 4, having notches in which said troughs rest, the cleat 5, upon which said bars rest, and the standards 9, substantially 95 100 as set forth.

ULRICH REIFFER.
